(57) **CLAIM**

The ornamental design for a light kit as shown and described.

DESCRIPTION

FIG. 1 is a top perspective view of a light kit;
 FIG. 2 is a bottom perspective view of the light kit of FIG. 1;

FIG. 3 is a top view of the light kit of FIG. 1;

FIG. 4 is a bottom view of the light kit of FIG. 1.

FIG. 5 is a side view of the light kit of FIG. 1;

FIG. 6 is a rear view of the light kit of FIG. 1;

FIG. 7 is a right side view of the light kit of FIG. 1; and,

FIG. 8 is a left side view of the light kit of FIG. 1.

Portions of the light kit and the ceiling fan environment shown in broken lines form no part of the claimed design.
